[57] **CLAIM**

The ornamental design for a tripod, as shown and de-
scribed.

DESCRIPTION

FIG. 1 is a typical perspective view of a tripod in the
telescoped position showing my new design;

FIG. 2 is a typical perspective view thereof on a smaller
scale with the legs fully extended;

FIG. 3 is a typical side elevational view of the upper
portion of the design of FIG. 1 on an enlarged scale
with the legs folded;

FIG. 4 is a side elevational view of FIG. 3 rotated 45°
with the legs partially extended;

FIG. 5 is a side elevational view of FIG. 3 rotated 45°;

FIG. 6 is a side elevational view of FIG. 4 rotated 45°;

FIG. 7 is a top plan view of FIG. 3 on an enlarged scale;

FIG. 8 is a bottom plan view of FIG. 7.

Portions of the top and bottom of FIGS. 3-6 have been
omitted for ease of illustration.
